METHOD OF AND MACHINE FOR FINISHING
THE EDGES OF SHEET MATERIALJoseph Fossa, Salem, Mass., assignor to United
Shoe Machinery Corporation, Paterson, N. J.,
a corporation of New Jersey

Application October 31, 1932, Serial No. 640,479

34 Claims. (Cl. 69—1)

This invention relates to the finishing of edges of pieces of sheet material such as leather by the application along such edges of an intense heat to shrink and sear the leather on one side and thereby cause the unshrunken side to curl toward the shrunken side.

Hitherto this operation has been carried out progressively, commonly by means of a machine which feeds the work past a stationary shrinking tool. Such a procedure is highly desirable when the work consists, as it does in large part, of parts of shoe uppers the edges of which have many curved portions of different curvatures, since such shoe parts may be presented to machines of this type indiscriminately regardless of differences in the curvature of the edges of such parts. Some shoe parts, however, which are used in large quantities, have edges of the same curvature or outlines. For example, the rear edges of toe tips commonly have radii of curvature of 8, 9 or 10 inches; and many factories use daily a large number of shoe tips the radii of curvature of all of which are exactly the same.

The general object of the present invention is to speed up the edge finishing operation on these and other suitable pieces. To this end the invention in one aspect relates to a method of finishing an edge of a piece of sheet material by applying a shrinking agent simultaneously to all points along an edge, or a considerable portion of an edge thereof. Preferably, heat is employed and is applied, together with pressure, to the edge of the bent-up margin of the piece, the pressure acting to displace the bend toward said edge so that the margin grows narrower until, by reason of this pressure and the searing and shrinking action of the heat first upon the edge and then upon the flesh side of the piece, the unshrunken grain side of the piece curls toward the shrunken flesh side to present a finished edge which is all grain.

In another aspect the invention relates to a machine by the use of which the method may be practiced. In the illustrated machine, which is designed to operate upon the rear edges of shoe tips, the work is held upon a support, its edge is bent up, and a suitably shaped shrinking tool is caused to apply heat and pressure to the edge to shrink the edge and to displace the bend, the shrunken edge being finally pressed against the work support. These steps follow each other in rapid succession, so that the entire edge is finished very quickly.

55 Although the method may be carried out by the

use of hand tools, it will preferably be practiced by the use of a suitable machine.

Referring now to the accompanying drawings,

Fig. 1 is a side elevation of a machine by use of which the method may be carried out, the parts of the machine being in positions corresponding to those in Figure 5.

Fig. 2 is a plan view, a portion of the cross-bar 131 of the shrinking tool carrier having been broken away. In this figure the parts of the machine are in positions corresponding to those in Figure 7.

Fig. 3 is a vertical longitudinal section with the parts in the same positions as in Figure 2,

Fig. 3^a is a detail in section showing how the shrinking tool is fastened to its carrier,

Fig. 4 is a horizontal section of the machine below the level of the work-engaging elements, the parts of the machine being in the same positions as in Figures 2, 3 and 7,

Figs. 5 to 9 are details in section showing successive stages in the finishing of the edge of a piece of work,

Fig. 10 is a section of a finished edge on a greatly enlarged scale, taken on the line X—X of Fig. 11, and

Fig. 11 is a plan of a finished toe tip with a portion partly torn away and bent up to show a section of the finished edge.

Referring first to Figures 5 to 11, the purpose of the invention, as has been explained, is to finish an entire edge, or a considerable portion of an edge, of a piece of leather, or the like, by the application of a shrinking agent, for example heat, simultaneously to all points along said edge.

The particular article chosen for illustration is a toe tip 100, the rear curved edge of which is to be finished. Referring more particularly to Figure 10 in which the grain side is lowermost, the grain surface extends over the rounded and compacted edge 200 to the point 300, and adjacent to this point on the flesh side is a narrow locality 400 which is more or less charred from the searing and burning effects of the hot shrinking tool whereby that side of the piece was shrunk to cause the unshrunken grain side to curl toward the flesh side. The showing of the finished piece in Figures 10 and 11 and of the piece in process of being operated upon in Figures 5 to 9 is not asserted to be strictly accurate, first be-

cause the dimensions of the portions of the piece involved in the operation are very small, second because it is very difficult to inspect the piece at various stages, such as those illustrated in Figures 7 to 9, wherein the portion of the work be-

cause the dimensions of the portions of the piece involved in the operation are very small, second because it is very difficult to inspect the piece at various stages, such as those illustrated in Figures 7 to 9, wherein the portion of the work be-

cause the dimensions of the portions of the piece involved in the operation are very small, second because it is very difficult to inspect the piece at various stages, such as those illustrated in Figures 7 to 9, wherein the portion of the work be-

cause the dimensions of the portions of the piece involved in the operation are very small, second because it is very difficult to inspect the piece at various stages, such as those illustrated in Figures 7 to 9, wherein the portion of the work be-

cause the dimensions of the portions of the piece involved in the operation are very small, second because it is very difficult to inspect the piece at various stages, such as those illustrated in Figures 7 to 9, wherein the portion of the work be-

ing operated upon is engaged on practically all sides by elements one of which is at a very high temperature, and third because no stage in which the hot shrinking tool is in contact with the piece can be prolonged to facilitate inspection.

In carrying out the method by the use of the illustrated machine, a toe tip 100 is placed upon a work support 17, the forward edge of which is convex to correspond to the curvature of the edge of the tip to be finished, with a narrow margin of the tip extending over a plate 21 and with the edge of the tip against two gages, one of which is shown at 19. This plate, which, as will presently appear, acts first to bend up a narrow margin of the tip and afterward to press the edge, has a concave edge to fit the convex edge of the work support 17. A treadle is now manipulated whereupon the following movements take place.

20 A shrinking tool 25 begins its downward movement carrying with it a presser foot or clamp 23 having an operative edge convexly curved to correspond to the curvature of the rear edge of the tip; and, when the parts have reached the positions shown in Figure 5, the tip has been clamped to the work support. The bending and pressing plate 21 moves up and to the left into the position shown in Figure 6 to bend up a narrow margin of the tip. It should be noted that the plate 21 now overhangs the work support 17 and that there is a space between the under face of the plate 21 and the upper face of the work support. The hot shrinking tool 25 continues its descent to apply an intense heat and pressure to the upwardly bent edge. The pressure displaces the bend in the toe tip toward the edge of the toe tip and forces this displaced bend into the space beneath the plate 21, as shown in Figure 7. At the same time the shrinking tool burns away a small portion of the edge and shrinks the edge. At this stage the lower operative face of the shrinking tool is still slightly above the level of the under face of the plate 21. The plate and the tool now preserve these relative positions while moving down together into the positions shown in Figure 8. During this movement the tool exerts a further searing action upon the edge and also a further shrinking action which extends to the flesh side of the tip, the shrinking action of the tool at all times causing the flesh side to shrink and thereby causing the grain side to curl toward the flesh side; and the plate 21 presses the bend (which gradually becomes the edge of the tip) against the work support. The plate 21 continues to press upon the edge while the shrinking tool continues its descent to the position shown in Figure 9 wherein its lower operative face is flush with the under face of the plate 21. The parts then return to their initial positions of rest ready to receive another tip.

Referring first to Figure 1, the machine comprises a base 27 having fastened to it an upright post 29 which is shaped in cross section as shown in Figure 4 to provide two dovetailed guide portions upon which the lower portions of two carriers 31, 33, one for the shrinking tool 25 and the other for the bending and pressing plate 21, are vertically slidable. Hardened steel gibs 32, 34 (Fig. 4) held in place by screws 36, 38 are provided respectively for the slides 31, 33. The work support 17 (Fig. 3) is fastened to a plate 35 by screws, one of which is shown at 37, the plate 35 being in turn fastened by screws 39 to the top of the upright posts 29 and being strengthened by two flat bars 30 (Figs. 2 and 1) which are fastened

to the under side of the plate 35 and to the post 29. The presser or clamping foot 23 (Fig. 2 and Fig. 5) is in the form of a bar having an edge curved to correspond to the curvature of the edge of the work support and fastened to the outer ends of two arms 41 the inner ends of which are pivoted about alined screws 43 which are threaded into the work support 17. The clamping foot is urged to swing downwardly at all times by tension springs 45 which are fastened respectively at their upper ends to screws 47 which are threaded into the arms 41 and at their lower ends to pins (Fig. 1) which are driven into depending lugs of the plate 35. The clamping foot is normally held in raised position when the machine is at rest by two hooks, one of which is shown at 51 (Fig. 3), the lower ends of which are fastened by screws 53 to the clamping foot and the upper ends of which extend over horizontal pins, one of which is shown at 55, driven into the cross-bar 131 of the shrinking tool carrier. In Figure 3 the shrinking tool carrier has been lowered, and consequently the pins 55 are no longer in contact with the hooks.

The shrinking tool carrier, as has been stated above, comprises a lower portion 31 which is vertically slidable on the vertical post 29. At its upper end this base portion is forked to provide two upwardly extending arms 31a between which the work support 17 extends; and upon the tops of these arms are block-shaped portions 31b to which the opposite ends of the cross-bar 131 are fastened by cap-screws 57 (Figs. 1 and 2). The shrinking tool is a curved bar of a length greater than the length of the rear edge of a toe tip of the largest size, and its lower work-engaging edge is narrow and curved to correspond to the curvature of the rear edges of the toe tips which are to be operated upon. This tool is made of a heat-resistant metal or alloy, for example ni-chrome, and is bored to receive a U-shaped electrical heat unit 59 (Fig. 3) to which line-wires 61 (Fig. 1) are attached so as to raise the tool to a temperature sufficient to shrink or sear the leather, a rheostat or other suitable device, not shown, being provided to regulate the heat. The shrinking tool (Figs. 3 and 3a) has at its upper portion two small projections 63 at right angles to each other which are received in channels in a holder 65, said holder having at its upper left-hand portion a rib undercut on one side which is held against an oblique wall formed on the cross-bar 131 by the conical heads of screws 67 which bear against an oblique face 69 on the holder. The shrinking tool 25 is held in place and steadied by three fingers, one of which is shown at 71, each of which engages with its lower end a horizontal groove formed in the shrinking tool. Each finger is firmly fastened to a flange on the cross-bar 131 by a screw 70, which passes through the flange and is threaded into the top of the finger, as well as by a flat bar 73 fastened to the edge of the flange by screws 75, said bar engaging a small projection at the upper end of each finger which extends into a recess in the flange. The heating unit 59 herein shown is a U-shaped member known as "sheath wire" which consists of a metal tube containing a coil of wire the coils of which are insulated from each other and from the tube by compressed powdered insulating material. The shrinking tool 25 with its holder 65 and the forked carrier 31, 131 is normally held raised, and its downward movement is limited by contact of the holder 65 with the square tops of three screws 77 (Figs. 2 and 3) which are threaded into the

clamping foot 23 and may therefore be adjusted. The shrinking tool carrier is moved down and then up again by a link 79 (Fig. 1) pivoted at its upper end at 81 to an ear formed on the slide 31 and at its lower end at 83 to the outer end of an arm 85 fast to one end of a rock-shaft 87, to the other end of which is fastened an upwardly extending arm 89, the upper end of which has pivoted in a horizontal bore the stem 91 of a short sleeve 93 through which a connecting rod 95 is slid able. A stop-nut 97, held against turning by a lock-nut 99, engages one end of the sleeve 93, and a strong compression spring 101 held in place by a nut 103 engages the other end of the sleeve. The connecting rod at its inner end is pivoted on a pin 105 fastened by a set-screw 107 in a boss on a sleeve 109 which is fast to a shaft 111. Consequently, when one revolution is imparted to the shaft 111, the shrinking tool will first be pulled down yieldingly through the spring 101 and then raised into and held in normal initial position.

The shaft 111 (Fig. 4) is driven in a manner presently to be described by a large gear 113 which meshes with a gear 115 of half its size fast to a driving shaft 117 so that two revolutions of the shaft 117 impart one revolution to the gear 113. The shaft 117 is driven from a constantly rotated pulley 119 through a clutch in such manner that, when a treadle rod is pulled down and then released, said shaft makes two revolutions and comes to rest. The clutch is of the one-revolution type but is fitted with an attachment whereby it imparts two revolutions to the shaft 117. The clutch itself will not be described since the details of its construction form no part of the present invention. It will be sufficient to explain (Fig. 1) that it is of the pin type and is thrown in by pulling down a treadle rod 121 normally held up by a compression spring 123 in a position determined by a collar 125 on the upper end of the rod which contacts with the under side of a stationary bracket 127. If no attachment were provided and the treadle rod were pulled down and then released, the shaft 117 would make one revolution. In order to hold the treadle rod down so that more than one revolution will be imparted to the shaft 117, a catch 129 pivoted at 132 and urged at all times to swing to the right by a tension spring 133 has a flange 135 which snaps over the top of the collar 125 as soon as the treadle rod is depressed by means of a treadle, not shown. This catch holds the treadle rod down until the shaft 117 has made a little more than one revolution whereupon the free end of the catch is engaged by the enlarged end of the connecting rod 95 and swung counter-clockwise about its pivot. This withdraws the flange 135 from engagement with the top of the collar 125 and permits the treadle rod 121 to rise so that the clutch will be thrown out at the end of the second revolution of the shaft 117. The machine then comes to rest with its parts in the positions shown in Figures 1 and 5.

The plate 21, which first moves up and to the left from the position shown in Figure 5 to that shown in Figure 6 and finally down to the position shown in Figure 9, is fastened (Fig. 3) by screws, one of which is shown at 137, to a slide 139 which is horizontally slidable on a horizontal extension of the carrier 33, said carrier, as has been described above, being itself vertically slid able on the post 29. The slide 139, and with it the bending and pressing plate 21, is urged at all times to move to the left (Fig. 1) by two tension springs, one of which is shown at 141, one end of

each of said springs being fastened to the shrinking tool carrier 31 and the other to the under side of the slide 139. In the positions shown in Figures 1 and 5, the plate 21 is prevented from movement to the left by contact of its forward edge with the edge of the work support 17. When, however, the carrier 33 is moved up, in a manner presently to be described, so as to raise the bending and pressing plate 21 above the level of the top of the work support, these tension springs move the plate to the left into the position shown in Figure 6, the extent of this movement being determined by an adjustable stop-screw 143 (Fig. 1) which is threaded through a depending lug on the slide 139 and contacts at its inner end with a part of the frame of the machine.

After the plate 21 has been moved up and to the left, as just described, and while the shrinking tool and the plate are being moved down from the position shown in Figure 6 to that shown in Figure 9, the plate has a tendency to move to the right. In order to insure that no such movement shall take place, a pair of locking members are provided. Referring to Figure 2, there is fastened along the rear edge of the slide 139 by means of screws 145 a bar 147. Firmly held by the projecting ends of said bar are the rear ends of two rods 149 having near their forward ends dovetailed notches 151 into which suitably shaped portions of the two block-shaped portions 31b of the fork of the shrinking tool carrier 31 move when the shrinking tool carrier descends, so that the shrinking tool and the plate 21 are prevented from horizontal movement or separation until after the completion of the operation upon the work.

The carrier 33 of the bending and pressing plate 21 is urged at all times to move up by a strong tension spring 153 (Fig. 1) fast at one end to the bracket 127 and at the other end to the outer end of an arm 155 the hub of which is fastened to a rock-shaft 157 by a set-screw 159. Also fast to this rock-shaft is a small arm 161 provided with a stop-screw 163 the inner end of which, by contacting with a vertical face 165 on a part of the frame, limits the extent of upward movement of the carrier 33. Fast to this rock-shaft beyond the arm 161, as viewed in Figure 1, is the hub of a forked arm 167 (see also Fig. 4) between the branches of the fork of which there is pivoted at 169 the lower end of a link 171, the upper end of which is pivoted at 172 to a lug on the carrier 33. With the construction thus far described, the heavy compression spring 153 will rock the shaft 157 from the position shown in Figure 1 to the position shown in Figure 3 so as to raise the carrier 33 whenever it is permitted to do so. The vertical movement of the carrier 33 is controlled by a cam 173 (Fig. 3). In the position of parts shown in Figure 1, this cam, which does not appear in that figure, is holding the arm 155 in its extreme left-hand position against the tension of the spring 153 and is therefore holding the carrier 33 in its lowermost position. Referring now to Figure 3, wherein the carrier 33 is shown in its uppermost position, the controlling cam 173 is fast to the shaft 111. At the proper time during the operation of the machine this cam engages and comes to rest in engagement with a roll 175 carried at the upper end of a crank 177 which is generally triangular in outline, said crank being rotatable on the stem of a screw 178 (Fig. 4) threaded into the end of the shaft 157 and having a horizontal bore to

receive one end of the pivot 169 which connects the lower end of the link 171 to the outer end of the forked arm 167. Movements of the crank 177 are, therefore, imparted to the rock-shaft 157. After the parts of the machine have reached the positions shown in Figure 9 and the bending plate 21 has been moved to the right in a manner presently to be described, the high part of the cam 173 will engage the roll 175 and swing the crank 177 to the left as viewed in Figure 3 to lower the carrier 33 and will come to rest with the parts of the machine in the positions shown in Figures 1 and 5. Before, however, the carrier 33 can be pulled down from the position shown in Figure 3, the slide 139 must be moved to the right. In order to accomplish this, a depending lug on the slide 139 is engaged by the upper end of an upright arm 179 pivoted at 181 and carrying a small roll 182 which is engaged at the proper time by the high portion of a cam 183 on the shaft 111.

It has been explained that the initial positions of the parts are shown in Figure 5, that the shrinking tool begins its downward movement, and that during this downward movement the plate 21 moves down. The shrinking tool moves downward continuously, and the downward movement of the plate 21 is imparted to said plate from the downwardly moving carrier. In order that the shrinking tool may first carry down the plate 21 to the position shown in Figure 8 and may then move down with respect to the plate into the position shown in Figure 9, the cross-bar 131 (Figs. 1 and 2) has threaded through a horizontal flange thereof two adjustable screw-bolts 185 located respectively above two abutments formed by the upturned ends 187 of the branches of a forked member 189, said member being pivoted about the common horizontal axis of two pivot-screws 191 (Fig. 2) threaded respectively into two upstanding lugs on a small plate 193 which is fastened to the slide 139 by cap-screws 194. The end of the stem of the forked member is attached by a spring 195 to a pin 197 driven into the frame, this spring being of sufficient strength in comparison with that of the spring 153 so that, when the screw-bolts 185 engage the upturned ends of the branches of the forked member 189, the plate 21 and its carrier 33 are pushed down against the force of the spring 153 which tends always to push the carrier up. When the shrinking tool 25 has reached the position shown in Figure 7, the screw-bolts 185 are in contact with the upturned end of the forked member 189, and consequently the shrinking tool 25 and the plate 21 then move down together into the position shown in Figure 8, their relative positions being the same as in Figure 7. The plate 21 can move down no farther, or at least not appreciably farther. In order to permit the shrinking tool to continue its downward movement to the position shown in Figure 9, in which its lower edge is on a level with the under face of the plate 21 or little below said level as may be desired, the forked member 189 (Fig. 3) is rocked in a counter-clockwise direction about its pivot-screws so as to lower the upturned ends of the branches of the forked member 189, said rocking being brought about by a cam 198 on the shaft 117 which engages the lower rounded end of a bar 199, the upper end of which is fastened to the rear end of the stem of the forked member 189. When the forked member 75 is thus rocked, its left-hand end (Fig. 3) is low-

ered, and the shrinking tool 25 is permitted to move down from the position shown in Figure 8 to that shown in Figure 9 to complete the operation upon the work.

It is desirable to cause the tool to dwell in this position for an interval which may be longer or shorter according to the thickness and hardness of the work. In order to provide for such a difference in the dwell of the shrinking tool on various kinds of leather, the shaft 111 is not rotated at a constant angular velocity but is caused to rotate faster in some of the angular positions of its path of rotation than in others; and mechanism is provided for controlling this harmonic motion of the shaft 111 so as to cause the shrinking tool to have a longer or shorter dwell as may be desired. To this end the shaft 111 (Fig. 4) has fast to it the hub of a slotted arm 201, and extending into the radial slot is a roll 203 rotatably mounted on a pin which passes through a bore in the gear 113 and is held firmly in place by a nut 205. This gear is rotatably mounted on a short spindle 207 fastened by a set-screw 208 in a boss near the middle of a lever 209, the hub of which is rotatable on the driving shaft 117. Pivoted to a lug on the lever at 211 is a small lever or latch 213 which is urged at all times to rotate about its pivot by a small compression spring 215, said latch having pivoted to it at one end at 217 a locking pin 219 which passes through a bore in the lever 209 and may be caused to enter any one of a series of holes 221 (Fig. 3) in an upstanding stationary member 223. Referring again to Figure 4, if the axis of rotation of the short shaft 207 is in alignment with the axis of the shaft 111, a uniform angular velocity will be imparted to the shaft 111 since the roll 203 will always be at the same distance from the axis of the shaft 111; and if, by manipulating the lever 209, the axis of the short shaft is held above or below the axis of the shaft 111, a harmonic motion will be imparted to the shaft 111. By moving the lever 209 into and locking it in different positions, the length of the dwell of the shrinking tool in the position shown in Figure 9 may be varied.

The edge gages 19, one of which appears in Figures 5 to 9 and both of which are shown in Figure 2, are mounted respectively at the outer ends of flexible stems 225 above openings in the plate 21, the inner ends of said stems being adjustably fastened to the plate 21 by screws 227 which pass through slots in said stems and are threaded into the plate. By reason of the flexible stems and the openings in the plate, the gages are permitted to yield downwardly as shown in Figures 7, 8 and 9 when the shrinking tool descends.

Assuming that the parts of the machine are in the positions shown in Figures 1 and 5, the operator places a toe tip upon the work support 17 with its rear edge against the gages 19, and depresses and then releases a treadle, not shown, which is attached to the lower end of the treadle rod 121 to start the machine. The connecting rod 95 is pulled to the right and, through the compression spring 101, the arms 89 and 85, and the link 79, starts the downward movement of the shrinking tool carrier 31, 131. The cam 173 (Fig. 3) which, by engagement with the roll 175, has been holding the plate 21 down against the pull of the heavy spring 153 (Fig. 1) runs off this roll. The spring 153 rocks the shaft 117 clockwise until the stop-screw 163 contacts with the vertical face 165 on a part of the frame there-

by raising the plate 21 above and out of contact with the edge of the work support 17. As soon as this occurs, the tension springs 141 pull the plate 21 to the left as far as the stop-screw 143 permits. The parts are then in the positions shown in Figure 6 with the margin of the tip bent up and the shrinking tool moving down. The shrinking tool continues its downward movement while the plate 21 remains stationary until the position of parts shown in Figure 7 has been reached, and the bend in the tip has been displaced toward the right into the space between the plate 21 and the work support. At this time, the lower ends of the screw-bolts 135 have engaged the upturned ends of the branches of the forked member 189 and farther downward movement of the shrinking tool carries the plate 21 down with it until the position shown in Figure 8 has been reached. At this time the cam 198 engages the lower end of the bar 199 and rocks the forked member 189 counter-clockwise, as viewed in Figures 1 and 3, thereby lowering the upturned ends of the branches of the forked member and permitting the shrinking tool to continue its downward movement until the parts have reached the positions shown in Figure 9. The parts are held in this position for an interval dependent upon the position in which the hand lever 209 has been previously locked. The connecting rod 95 (Fig. 1) then moves to the left to raise the shrinking tool; and, during this raising movement, the cam 183 (Fig. 3) by engaging the roll 182 on the arm 179 moves the slide 139, and with it the plate 21, to the right. Finally, the cam 173 engages the roll 175 and pulls the carrier 33 down so that the machine comes to rest with the parts in the positions shown in Figures 1 and 5.

Throughout the description of the invention given above, reference has been made to finishing an edge of the piece of work by applying a shrinking heat simultaneously to all points along said edge. It will be understood, or course, that the invention is applicable to the finishing of any suitable portion of an edge as distinguished from the progressive method of finishing in which very small portions are finished in succession. The expression "applying heat simultaneously to all points along the edge" which occurs in the appended claims is intended to include the application of heat in the manner described throughout a considerable extent along the edge whether or not the application is made along the entire edge. Although in the particular machine herein illustrated the work support is stationary and certain movements are imparted to the bending plate and to the tool, it should be understood that suitable relative movements of the parts will produce the desired result and that the invention, so far as the machine is concerned, is not limited in the scope of its application to the particular machine which has been shown and described.

Having described the invention, what I claim as new and desire to secure by Letters Patent of the United States is:

1. The method of finishing the edge of a piece of leather or the like which comprises holding the piece from lateral and endwise movement, forming a bend along an edge thereof, applying a shrinking heat and pressure to said edge to sear and shrink said edge and to displace the bend, and pressing the shrunken edge.

2. The method of finishing the edge of a piece of leather or the like which comprises holding the piece from lateral and endwise movement, form-

ing a bend along an edge thereof, applying pressure and heat to said edge to displace the bend toward the edge and to sear and shrink the piece on one side thereof whereby the unshrunken side curls toward the shrunken side, and pressing the curled edge.

3. The method of finishing the edge of a piece of leather or the like which comprises holding the piece from lateral and endwise movement, forming a bend along an edge thereof, applying pressure and heat to said edge, to displace the bend toward the edge and to sear and shrink the piece on one side thereof whereby the unshrunken side curls toward the shrunken side, and pressing the curled edge while continuing the application of heat.

4. The method of finishing the edge of a piece of leather or the like which comprises holding the piece from lateral and endwise movement, forming a bend along an edge thereof, applying a shrinking searing heat and pressure to said edge to burn away a portion of the edge, to displace the bend toward said edge and to shrink the piece on one side so that the unshrunken side curls toward the shrunken side, and pressing the curled edge.

5. The method of finishing the edge of a piece of leather or the like which comprises holding the piece from lateral and endwise movement, forming a bend along an edge thereof, applying a shrinking searing heat and pressure to said edge to burn away a portion of the edge, to displace the bend toward said edge and to shrink the piece on one side so that the unshrunken side curls toward the shrunken side, and pressing the curled edge while continuing the application of heat.

6. A machine for finishing the edge of a piece of leather or the like having, in combination, cooperating members for holding the piece from lateral and endwise movement, and means relatively movable with respect to said holding members for applying a shrinking heat simultaneously to all points along an edge thereof.

7. A machine for finishing the edge of a piece of leather or the like having, in combination, work clamping means for holding the piece stationary, and means relatively movable with respect to said clamping means for applying a shrinking tool simultaneously to all points along an edge thereof.

8. A machine for finishing the edge of a piece of leather or the like having, in combination, means for holding the piece from lateral and endwise movement, means for applying a shrinking heat simultaneously to all points along an edge thereof to shrink one side of the piece along the edge and cause the unshrunken side to curl toward the shrunken side, and means for pressing the curled edge.

9. A machine for finishing the edge of a piece of leather or the like having, in combination, means for holding the piece from lateral and endwise movement, means for applying a shrinking heat simultaneously to all points along an edge thereof to shrink one side of the piece along the edge and cause the unshrunken side to curl toward the shrunken side, and means for pressing the curled edge while the shrinking tool is still operating upon the piece.

10. A machine for finishing the edge of a piece of leather or the like having, in combination, means for clamping the piece adjacent to an edge thereof, and means for applying a shrinking heat simultaneously to all points along said edge.

11. A machine for finishing the edge of a piece of leather or the like having, in combination, means for clamping the piece adjacent to an edge thereof, a shrinking tool shaped to conform to the outline of said edge, and means for causing relative movement of approach between the clamping means and the tool to cause the tool to be applied along said edge. 5
12. A machine for finishing the edge of a piece of leather or the like having, in combination, a work support, means for holding the piece on the support, a shrinking tool shaped to correspond to the outline of the edge of the piece, and means for causing relative movement of approach between the support and the tool to cause the tool to be applied along the edge of the piece. 10
13. A machine for finishing the edge of a piece of leather or the like having, in combination, a work support, means for holding the piece on the support, a shrinking tool shaped to correspond to the outline of the edge of the piece, and yielding means for causing relative movement of approach between the support and the tool to cause the tool to be applied along the edge of the piece. 15
14. A machine for finishing the edge of a piece of leather or the like having, in combination, a work support having an edge shaped to correspond to the outline of the edge of the piece, means for clamping the piece to the support with a margin of the piece projecting beyond the edge of the work support, a member for bending up the margin of the piece, and a shrinking tool for applying heat simultaneously to all points along the bent-up margin. 20
15. A machine for finishing the edge of a piece of leather or the like having, in combination, a work support having an edge shaped to correspond to the outline of the edge of the piece, means for clamping the piece to the support with a margin of the piece projecting beyond the edge of the work support, a member having an edge shaped to fit the edge of the work support for bending up the margin of the piece, and a shrinking tool for applying heat to the bent-up margin. 25
16. A machine for finishing the edge of a piece of leather or the like having, in combination, a work support having an edge shaped to correspond to the outline of the edge of the piece, means for clamping the piece to the support with a margin of the piece projecting beyond the edge of the work support, a member having an edge shaped to fit the edge of the work support for bending up the margin of the piece, and a shrinking tool shaped to correspond to the outline of the edge of the piece for applying heat to the bent-up margin. 30
17. A machine for finishing the edge of a piece of leather or the like having, in combination, a work support having an edge shaped to correspond to the curvature of the edge of the piece, a bending and pressing plate having an edge shaped complementary to that of the work support, a shrinking tool shaped to correspond to the curvature of the edge of the piece, means for holding the piece stationary with respect to the work support, and means for causing the piece, while so held, to be operated upon by the shrinking tool and by the bending and pressing plate. 35
18. A machine for finishing the edge of a piece of leather or the like having, in combination, a work support having an edge shaped to correspond to the curvature of the edge of the piece, a bending and pressing plate having an edge shaped complementary to that of the work support, a shrinking tool shaped to correspond to the curvature of the edge of the piece, means for holding the piece on the support, means for raising the bending plate to bend up the margin of the work and hold it bent up, a shrinking tool normally located at a level above that of the bent-up margin, and means for moving the tool 40
- shaped complementary to that of the work support, a shrinking tool shaped to correspond to the curvature of the edge of the piece, means for clamping the piece to the work support with its margin extending over the plate, means for causing the plate to overhang the work support in spaced relation thereto in such manner that the margin of the piece is bent up, means for causing the shrinking tool to shrink the edge of the piece and to crowd a portion of the piece into the space between the plate and the work support, and means for thereafter causing relative movement of approach between the plate and the work support to exert pressure upon this portion. 45
19. A machine for finishing the edge of a piece of leather or the like having, in combination, a work support and a bending and pressing plate having adjacent edges shaped complementary to each other to correspond to the outline of the edge of the piece, means for moving the plate into a position in which it overhangs and is spaced above the work support, a shrinking tool shaped to correspond to the outline of the edge of the piece, and means for moving the tool toward the work support while maintaining it close to the edge of the plate and for causing relative movement of approach between the work support and the plate. 50
20. A machine for finishing the edge of a piece of leather or the like having, in combination, a work support, means for clamping the piece upon the support, a bending and pressing plate, means for producing relative movement between the support and the plate to bend up a narrow margin of the piece and to cause the plate to overhang and to be spaced from the support, a shrinking tool shaped to correspond to the outline of the edge of the piece, means for causing the tool to exert pressure upon the edge to displace the bend into the space between the plate and the support, and means for producing relative movement of approach between the support and the plate to exert pressure upon that portion of the piece which is between them. 55
21. A machine for finishing the edge of a piece of leather or the like having, in combination, a work support, means for clamping the piece upon the support, a bending plate, means for producing relative vertical and horizontal movement between the support and the plate to bend up a narrow margin of the piece, a shrinking tool shaped to correspond to the outline of the edge of the piece, means for causing the tool to exert pressure upon said edge, and means for producing relative movement of approach between the tool and the work support. 60
22. A machine for finishing the edge of a piece of leather or the like having, in combination, a work support, a bending plate, means for clamping the piece upon the support with a margin thereof resting upon the plate, a shrinking tool shaped to correspond to the outline of the edge of the piece, means for moving the plate into a position in which it overhangs the support and is spaced above the support, and means for moving the tool downward, and for moving the plate downward with the tool. 65
23. A machine for finishing the edge of a piece of leather or the like having, in combination, a work support, a bending plate, means for clamping the piece on the support, means for raising the bending plate to bend up the margin of the work and hold it bent up, a shrinking tool normally located at a level above that of the bent-up margin, and means for moving the tool 70
- 75

toward the support while maintaining it close to the edge of the raised bending plate.

24. A machine for finishing the edge of a piece of leather or the like having, in combination, a work support, a bending plate, means for clamping the piece on the work support, means for causing the bending plate to bend up the margin of the work, a shrinking tool, and means operating first to move the tool toward the support while the plate remains stationary, then to move both the tool and the plate toward the support, and finally again to move the tool but not the plate toward the support.

25. A machine for finishing the edge of a piece of leather or the like having, in combination, a work support, means for clamping the piece upon the support, a bending plate, means for moving the plate into a position in which it overhangs the work support and is spaced above it to bend up a margin of the piece, means for locking the plate and the work support against horizontal movement of separation, a shrinking tool shaped to correspond to the outline of the edge of the piece, means for moving the tool toward the work support to sear and shrink the leather on one side along the edge and thereby cause the unshrunken side to curl toward the shrunken side, and means for lowering the bending plate to press the curled edge.

26. A machine for finishing the edge of a piece of leather or the like having, in combination, a work support, a bending plate, means for clamping the piece upon the support with a margin of the piece bent up against an edge of the plate, a shrinking tool shaped to correspond to the outline of the edge of the piece, and means for causing the shrinking tool to apply heat and pressure to the edge of the piece.

27. A machine for finishing the edge of a piece of leather or the like having, in combination, a work support, a bending plate, means for clamping the piece upon the support with a margin of the piece bent up against an edge of the plate, a shrinking tool shaped to correspond to the outline of the edge of the piece, means for causing the shrinking tool to apply heat and pressure to the edge of the piece, and means for causing relative movement of the work support and the bending plate to press the edge.

28. A machine for finishing the edge of a piece of leather or the like having, in combination, a work support, a bending plate, means for clamping the piece upon the support with a margin of the piece bent up against the edge of the plate,

a shrinking tool shaped to correspond to the outline of the edge of the piece, means for causing the shrinking tool to apply pressure to the edge of the piece to force the bend into the space between the lower face of the plate and the upper face of the support, and means for causing relative movement of approach between the plate and the support to press the bend.

29. A machine for finishing the edge of a piece of leather or the like having, in combination, a support for the piece, a shrinking tool shaped to correspond to the outline of the edge, means for causing the tool to press against the piece, to dwell for an interval in contact with it and then to be separated from it, and means for varying the interval of the dwell.

30. A machine for finishing the edge of a piece of leather or the like having, in combination, a support for the piece, a shrinking tool for shrinking the piece on one side along the edge thereof to cause the unshrunken side to curl toward the shrunken side, a member for pressing the curled edge, and means for causing the tool and the pressing member to act simultaneously upon all points along said edge.

31. A machine for finishing the edge of a piece of leather or the like having, in combination, a support for the piece, a plate for bending up the margin of the piece, a shrinking tool shaped to correspond to the outline of the edge to be finished, means for moving the tool toward the support, and adjustable means for limiting the extent of such movement.

32. The method of finishing the edge of a piece of leather or the like which comprises holding the piece from movement with respect to a support, forming a bend along an edge thereof, applying a shrinking agent to sear and shrink said edge, and pressing the shrunken edge against the support.

33. The method of finishing the edge of a piece of leather or the like which comprises holding the piece from lateral and endwise movement, bending up all points along an edge thereof simultaneously, and applying a shrinking agent simultaneously to all points along said bent-up edge.

34. The method of finishing the edge of a piece of leather or the like which comprises holding the piece from lateral and endwise movement, bending up all points along an edge thereof simultaneously, applying a shrinking agent simultaneously to all points along said bent-up edge, and pressing the shrunken edge.

JOSEPH FOSSA.
